IGNACIO LAZAGA, OF HABANA, CUBA.

FEEDING MECHANISM FOR CIGARETTE-PACKAGING MACHINES.

Application filed March 25, 1926. Serial No. 97,323.

This invention relates to an improvement in feeding mechanism for cigarette packaging machines.

The object of the invention is to provide 5 an improved feeding mechanism which will arrange and feed the articles to be packaged on different elevations, in order that one row of articles may be positioned above the other. This also permits of allowing the 10 articles to be arranged in a particular relation to each other and also eliminates the necessity of receiving the entire number of articles to be packaged from the feed hopper in their bunched relation at one time. 15 A further object of the invention is to provide an improved feeding mechanism for packaging machines which will properly feed and arrange oval cigarettes, so that they may be bunched in their proper relation to 20 be wrapped.

Heretofore, it has been customary to wrap oval cigarettes by hand, which necessarily takes a considerable amount of manual labor and necessitates the employment of a number 25 of employees to package a small quantity of cigarettes, and, in order to obviate this objection, this improved mechanism is provided which is so constructed that it will properly arrange the oval cigarettes in their 30 bunched relation so as to permit the packaging mechanism to fold the wrapper around the same. The ordinary feeding mechanism for round cigarettes cannot be utilized for this purpose because the oval 35 cigarettes must be arranged in a particular relation to each other and, if the mechanism for feeding the round cigarettes were used, no provision would be made for properly and symmetrically arranging the oval cigarettes. 40

After the cigarettes have been properly fed and arranged in their correct formation and bunched relation, the same form of wrapping mechanism may be employed to 45 fold the wrapper around the same, as is ordinarily used with the round cigarettes.

In carrying out this invention and these objects, my improved feeding mechanism includes a hopper divided into a plurality of 50 compartments arranged side by side, through each of which a feed-belt of a special construction passes, in order to convey the ciga-

rettes one at a time from each of these compartments. Specially arranged platforms are provided adjacent the ends of the feed-belts in order to receive the cigarettes therefrom in their properly formed relation and these platforms are arranged on different elevations in order that one row of cigarettes may be positioned above the other, so 55 that as the plunger passes over the platform, moving the cigarettes therefrom into the transferring mechanism, it will push one row of cigarettes under or over the other, thus giving the entire number of bunched cigarettes their proper formation to receive the 60 wrapper which is about to be folded there-around. Agitator rollers are provided within the bottom of the hopper in order to keep the cigarettes feeding downward therein 65 continually and also in order to allow only the proper number of cigarettes to be carried from the compartments of the hopper 70 by the feed-belt. These agitator rollers also serve to insure that each individual cigarette will be placed and held at its proper angle with relation to the others, in order to 75 allow the cigarettes to be properly bunched, ready to be wrapped. It is preferable to arrange the oval cigarettes with the longest 80 diameter at an obtuse angle to a horizontal plane.

In the accompanying drawings:—

Fig. 1 is a plan view of my improved feeding mechanism; 85

Fig. 2 is a side elevation partly in section of the same and also showing a part of the driving mechanism therefor;

Fig. 3 is a transverse sectional view through the transferring mechanism; 90

Fig. 4 is a vertical sectional view through the rear roller for the feed-belt;

Fig. 5 is a partial vertical section there-through at right angles to Fig. 4; 95

Fig. 6 is a transverse vertical section through the front drive roller for the feed-belt;

Fig. 7 is a detail side elevation of the same; 100

Fig. 8 is a side elevation of the cam plate;

Fig. 9 is a detail sectional view through the feeding platforms;

Fig. 10 is a top plan view of the cross-head and plunger bar;

- Fig. 11 is a side elevation of the same;
Fig. 12 is a side elevation of the plunger finger and bar partly in section;
Fig. 13 is a side elevation of the feed hopper and the door therefor;
Fig. 14 is a side elevation of the chain tension gears;
Fig. 15 is a side elevation of the driving cam for the plunger crosshead;
10 Fig. 16 is a plan view of one of the cover plates for the platform compartments;
Fig. 17 is a vertical sectional view through the lower end of the feed hopper showing a support for the upper side of one of the feed-belts; and
15 Fig. 18 is an end view of a completed package of oval cigarettes.

Since this improved mechanism, which feeds and arranges oval cigarettes in their proper form and relation to be wrapped, may be used with any suitable wrapping mechanism, it is not considered necessary to show any such wrapping mechanism in the drawings, since the various forms are well 20 known and familiar to those skilled in the art.

The top plate 1 of the packaging machine table supports and has extending laterally therefrom the side bars 2, which are braced, 25 by suitable transverse bars 3 and which carry a feed hopper 4, mounted thereon. The hopper 4 is provided with a longitudinal partition 5 therein and has sloping ends 6 and 7 providing compartments 8 and 9 therein, 30 which are intended to receive and contain the cigarettes to be packaged. As shown in Fig. 13, a suitable door 10 is mounted on one side of each of the compartments 8 and 9 and is hinged at 11 in order to permit of the 35 swinging of this door in its closed position. A spring catch 12 engages and holds the door in its closed position.

As shown in Fig. 1, the lower end of the feed hopper 4 is open in order to allow the cigarettes to feed downwardly therefrom, and in order to insure that the cigarettes will not become clogged in the compartments of the hopper, agitator rollers 13 are mounted in the compartments on the drive 40 shafts 14 and 15, which are mounted in bearings 16, carried on the sides of the bars 2. The shafts 14 and 15 carry pulleys 17 at corresponding ends thereof, about which a belt 18 extends in order to drive the shafts and the agitator rollers in the same direction and at the same rate of speed. The shaft 14 extends outwardly from one of its bearings 16 and carries a pulley 19 thereon, about 45 which a drive-belt 20 extends, the opposite end of the belt 20 passing around a drive pulley 21, mounted on the stub shaft 22, which is driven by a chain wheel 23, as shown in Fig. 14. The stub shaft 22, which carries the pulley 21 and the chain wheel 23, is adjustably mounted in the bracket 24

extending laterally from and secured to the machine table 1. A drive chain 25 passes around the chain wheel 23 and around a drive chain wheel 26, mounted on the shaft 27, the purpose of which will be hereinafter described, and the chain further extends around an idler chain wheel 28 also carried by the bracket 24. The sprocket chain 25 is driven from a chain wheel 29, mounted upon and driven by a driving shaft 30, as shown in Fig. 2. The driving shaft 30 is driven from a main driving shaft 31, by means of bevelled gears 33 on the ends thereof. This driving mechanism is similar to that shown in my prior Patent 1,518,081, December 2, 1924.

The shaft 27 is journaled in suitable bearings in the side plates 2 and constitutes the main drive shaft for the conveyor or feed-belts, which receive and transfer the cigarettes from the compartments of the hopper. As shown in Figs. 6 and 7, the shaft 27 has feed-rollers 34 securely mounted thereon to be rotated thereby. These rollers 34 receive, 85 guide, and drive the conveyor belts 35 of which there are preferably two in number, as shown in Fig. 1. The belts 35 pass around idler drums 36 at their rear ends, which drums are mounted upon a shaft 37 carried by and journaled in the side plates 2.

Each of the belts 35 carries a plurality of feed bars 38, as shown in detail in Figs. 4 and 5, each of which has one side 39 thereof straight and substantially at right angles to the belt 35, the opposite side being cut out and rounded as at 40, providing a compartment 41, between each of the bars 38, which compartment is only substantially large enough to receive one cigarette. The concave side 40 is so formed as to position the cigarette, which fits thereagainst, at its proper angle to be bunched and wrapped with the other cigarettes. The bars 38 are slightly spaced apart in order to provide a more flexible belt and these bars are secured to the belts 35 by means of set-screws 42, the heads of which extend outwardly from the belts and are received in suitably spaced openings 43 in the front drums 34, forming a driving connection between the drums 34 and the belts 35. As shown particularly in Fig. 5, recessed portions 44 are provided in each of the bars 38, into which the screws 42 extend. The screws 42 are staggered in the alternate bars 38, as clearly shown in Fig. 5, and consequently the holes 43 are likewise staggered to correspond. The heads of the screws are received in suitable grooves 45, formed in the surface of the rear drums 36, in order to provide a frictional connection between the belts 35 and these drums 36.

As shown in Fig. 1, an upper platform 46 is arranged adjacent the end of one of the belts 35 and has prongs 47 extending down-

wardly therefrom into the recessed portions 44 of the bars 38, in order to receive the cigarettes from the conveyor belts and direct them up over the platform out of the 5 belts. The platform is made substantially L-shaped, as shown in Fig. 1, and is received between and secured to the bars 48. A similar platform 49 is provided for the other belt 35 and receives the cigarettes therefrom but, as shown in Fig. 9, these two platforms 46 and 49 are on different elevations so that one row of cigarettes will be carried to an elevation lower than the other, in order to be positioned therebelow when the cigarettes 10 are properly bunched. Cover plates 50 and 51 are provided for the compartments 52 and 53, formed between and over the platforms 46 and 49. The cover plates 50 and 51 are provided with fingers 54, which project into the recessed portions 44 of the bars 38 but above the cigarettes carried thereby, in order to hold the cigarettes down in their proper positions while guiding the same over the platforms. As previously stated, 15 the cigarettes are arranged at their proper angle by means of the concave sides 40 of the bars 38 and in order to prevent the cigarettes from turning over or getting out of this proper position, the compartments 20 52 and 53 are made of a less width than the length of the greatest diameter of the oval cigarettes. As shown in Fig. 9, suitable end plates 55, supported by means of extensions 56, are provided for holding the ends of 25 the cigarettes in the conveyors to prevent them from moving longitudinally or being accidentally displaced within the conveyor belts.

As a further means of holding the cigarettes in their proper positions and relation, 30 suitable foot-plates 57 are pivotally secured to the side of the hopper as shown in Fig. 13, in order to bear down upon the tops of the cigarettes as they are carried by the 35 conveyor from the hopper.

The cigarettes are moved from the compartments 52 and 53 by means of a plunger fingers 58, which as shown in Fig. 12 is provided with a longitudinal slot 59, in order 40 to clear the platform 46 and move the cigarettes over both of these platforms 46 and 49. The plunger finger 58 is provided with an upwardly extending flange 60, at one end thereof, which is securely riveted to a plunger bar 61, shown in detail in Figs. 10 to 12. The plunger bar 61, at its outer end, is guided between the upstanding guide plates 62 carried by the crosshead 63 and this plunger bar is mounted on a block 64, 45 pivoted upon a pivot pin 65, which extends through the plates 66 also carried by the crosshead 63. The extreme outer end of the plunger bar 61 has a plate 67 secured thereto which extends outwardly beyond the plunger bar 61 and a similar plate 68 is se-

cured to and projects outwardly from the lower side of the crosshead 63. A relatively strong spiral spring 69 is connected between the plates 67 and 68, as shown in Fig. 11.

The crosshead 63 is mounted in suitable guides 70 as shown in Fig. 1 and this crosshead with its plunger bar 61 is reciprocated by means of a lever 71, pivoted as at 72 to the frame of the machine. The lever 71 carries a roller 73 which bears against a driving cam 74, shown in Fig. 15, which cam is mounted upon a shaft 75, geared to and driven from the main driving shaft 31 by means of the gears 76 and 77, all of which 75 is clearly shown in Fig. 2. The cam 74 is provided with a slightly flattened portion 78, as shown in Fig. 15, for the purpose of substantially stopping the movement of the crosshead to allow the plunger finger to be moved upwardly when it has reached the limit of its outer stroke.

For this purpose also the cam plate, shown in Figs. 8 and 9, provided to regulate the upward and downward movement of the plunger bar 61. This cam plate is formed of a back plate 79 which carries a cover plate 80 secured thereto by suitable screws 81. The bar 82 is pivoted to the back plate 79, as at 83, and this bar is provided with bevelled ends 84, as shown in Fig. 8, for guiding the movement of the plunger finger. One end of the back plate 79 is provided with a suitable abutment 85 which has a diagonal face 86 thereon for guiding the plunger finger downward again, when it has substantially reached the limit of its rearward movement. For the purpose of guiding this plunger finger 58, a roller 87 is secured to the outer end of the plunger bar 105 61, as shown in Fig. 12, and when the plunger finger has reached the limit of its outward movement, the spiral spring 69, bearing down upon the rear end of the plunger bar 61, causes the plunger finger to 110 move upward away from the platforms 46 and 49, and the roller 87 is guided over and along the upper surface of the bar 82 by the bevelled edge 84 thereof. The roller 87 thus moves back along the bar 82 until it reaches and strikes the inclined surface 86 of the abutment 85, when it moves the forward end of the bar 82 downward against the tension of the spring 88, bearing against the pin 89 projecting from the bar 82, through the slot 90 formed in the back plate 79. The roller 87 moves around and over the bevelled end 84 of the bar 82 and is moved downward into alignment with the compartments 52 and 53 again in position to engage and move the cigarettes therefrom. As shown in Fig. 16, small wire springs 91 extend inwardly over the surface of the cover plate 50 and extend through the perforations 92 therein, the outer ends

115 120 125 130

of these springs 91 being bent to engage and retain the innermost cigarette in the compartment 52 after the plunger finger 58 has moved the remaining cigarettes away from 5 in front of this position and through the compartment 52 and into a transferring mechanism. When the plunger finger 58, on its forward stroke, removes a predetermined number of cigarettes from those on 10 the platform 46, the continuous feeding movement of the innermost cigarette and to a lesser degree of those behind it is temporarily arrested, due, of course, to the fact that the innermost or the first cigarette 15 of the remaining ones cannot advance while the plunger finger 58 moves past it. Consequently, while the innermost cigarette is thus held up, this cigarette and several others behind it are being increasingly compressed which, in turn, is due to the continuous travel of the feed belt. As soon as 20 the plunger finger 58 has passed the innermost cigarette, that is, just cleared it, it would have the tendency, on account of its 25 having been held under compression, to jump ahead and clear the others behind it and thus being free and no longer in contact with the others, lose its angular position, but this is prevented by the springs 30 91. Thus, these wire springs 91 serve to temporarily retain the cigarettes in their proper formation and to prevent the spreading of the innermost ones within the compartment 52 after the plunger 48 has moved 35 the charge from the compartment 52 and until the plunger has returned to its initial position to engage the same. The springs 91 frictionally engage the foremost cigarettes until they are forced forward by the 40 following ones but this temporary restraint will prevent them from spreading out in the compartment 52.

The transferring mechanism 93 is preferably the same as that shown in my prior 45 Patent No. 1,518,081, December 2, 1924, except for the fact that the plunger 94, which engages and moves the bunched cigarettes through the transferring mechanism is provided with notches 95 therein, as shown in 50 Fig. 3, in order to clear guide studs 96, carried by screws 97 from the cover plate 98 of this transferring mechanism. These screws 97 are adjustable through slots 99 formed in this top plate 98, as clearly shown 55 in Fig. 1.

With this form of transferring mechanism, there is ordinarily an overmovement of the plunger 94 and in order to prevent the cigarettes from spreading apart during 60 this overmovement, these guide studs 96 are provided. The cigarettes are moved into engagement with these guide studs 96 by means of the plunger finger 58 where they are held between the studs and suitable 65 means connected with the transferring 40 mechanism, until the plunger 94 is moved back and engages the bunched cigarettes, moving them through the transferring mechanism 93 and in position to be engaged and moved through the packaging mechanism 70 for folding the wrapper around the bunched cigarettes. This wrapping mechanism may be of any suitable construction and may, in fact, be the same as shown in my prior Patent No. 1,518,081, so it is not considered 75 necessary to show or describe the same in this application.

As shown in Fig. 17, a suitable guide plate 100 may be provided for engaging the under 80 side of each of the belts 35 or any other suitable mechanism may serve this purpose, which is merely to support the belt during its movement through and from the feed hopper. Guide rollers might also serve this 85 purpose.

The operation of the machine will be apparent from the above description, but to recapitulate, the cigarettes are placed in the two compartments 8 and 9 of the feed hopper 4, where they are constantly fed downward therein by means of the agitator rollers 13, which are driven in the same direction and at a slower speed than the conveyor belt shafts. Although the agitator 90 rollers 13 are in fact driven in the same direction as the shafts, which carry the feed belt drums, the direction of travel of the agitator rollers is opposite to that of the feed belts at the point where they are closest. The rotation of the agitator rollers in connection with the movement of the feed belts 95 causes the cigarettes to tend to rotate as a mass in the hopper. This rotary agitating action takes place between the two respective agitator rollers for each belt, as well as between the outermost agitator roller and the side of the hopper. Besides agitating the 100 cigarettes, the rollers 13 also serve to move the cigarettes into their proper angular position with relation to the feed belts in the 110 event that any cigarette has dropped into the flutes of the feed belt in any but the proper position. It sometimes happens that the cigarettes position themselves in such a way as to bring the longest diameter at 115 right angles to the feed belt, and if this happens, the agitator rollers will turn the cigarettes and position them properly against the concave sides of the feed bars or flutes. This action is also helped by the 120 resilient foot plates 57 which not only tend to turn the cigarettes to their proper positions but prevent the cigarettes from turning up accidentally. Thus, these agitator rollers serve to prevent more than one cigarette 125 from being carried by each of the belt fingers or bars 38 and also insure that the oval cigarettes will be moved over in their proper diagonal positions against the concave side 40 of each of the feed bars 38. The ciga- 130

rettes are then carried from the feed hopper and held down in their proper diagonal positions by means of the foot-plates 57, until they reach and are guided over the platforms 46 and 49, which are so close together that the cigarettes cannot turn in the compartments 52 and 53, and thus they are held in their diagonal position throughout the length of their movement and 5 when moved together through the compartments 52 and 53, the two rows of cigarettes will assume their final diagonal positions, shown in Fig. 18. The cigarettes are moved through these compartments by 10 means of the finger 58 which is operated from the crosshead 63 and when this finger has reached the limit of its movement, it is moved upward by means of the spring 69 and the roller 87 is guided back in its 15 elevated position over the upper edge of the bar 82 and is again guided downwardly by means of the inclined surface 86 of the abutment 85 on the back plate 79, bringing the plunger down into its proper position again 20 to engage another charge of cigarettes. The cigarettes are thus moved by means of the finger 58 into the transferring mechanism 93, which moves the cigarettes across the machine and through the packaging mechanism. 25

It will thus be seen that oval cigarettes may be so arranged and delivered from the hopper in a formation which will allow them to be packaged in compact and convenient form in such a manner that they may be moved through the packaging mechanism and wrapped by the same mechanism which is ordinarily used for wrapping round cigarettes. Provision is also made for delivering various rows of cigarettes at different elevations in order to position one row above the other during the final bunching of the cigarettes. 35

I claim:

1. Feeding mechanism for packaging machines including a feed hopper having a plurality of compartments arranged therein, endless conveyors for feeding the articles from said compartments along substantially 45 the same horizontal plane, and means for receiving and directing the articles from each of the endless conveyors along a different horizontal plane from the articles delivered from the remaining conveyors. 50

2. Feeding mechanism including a compartment, means for feeding articles thereto, a plunger finger for feeding said articles through said compartment, a plunger bar carrying said finger, a reciprocating cross-head to which said plunger bar is pivotally connected, and resilient means for normally holding said plunger finger out of alignment with the compartment. 55

3. Feeding mechanism including a compartment, means for feeding articles thereto,

a plunger finger for feeding said articles through said compartment, a plunger bar to which said finger is attached, a reciprocating crosshead for pivotally supporting said plunger bar, plates extending outwardly 70 from the plunger bar and crosshead, a spring connected with the plates for normally tending to hold the finger out of alignment with the compartment, and means for moving said finger into alignment with 75 the compartment when it has substantially reached the limit of its rearward movement.

4. Feeding mechanism including a compartment, means for feeding articles thereto, a plunger finger for feeding said articles 80 through said compartment, a plunger bar to which said finger is attached, a reciprocating crosshead for pivotally supporting said plunger bar, plates extending outwardly 85 from the plunger bar and crosshead, a spring connected with the plates for normally tending to hold the finger out of alignment with the compartment, means for reciprocating the crosshead to move the finger forward through the compartment and back out of 90 the compartment, and a cam bar for moving said plunger into alignment with the compartment when it has substantially reached the limit of its rearward movement. 95

5. Feeding mechanism including a compartment having a partition therein, a plunger finger having a substantially horizontal slot therein in position to pass over the partition to transfer articles through 100 said compartment, means for moving said plunger finger through the compartments, means for moving the plunger finger out of alignment with the compartment when it has substantially reached the limit of its forward movement, a cam roller carried by 105 said plunger finger, and means for guiding the rearward movement of said plunger finger including a back plate, a cam bar pivotally connected therewith, a top plate carried by said back plate in position to receive the cam roller between said top plate and the pivot bar, resilient means for normally holding said bar in its upward position, and an abutment carried by said back plate and having a sloping side in position 110 to engage the roller and move the plunger finger downward into alignment with the compartment when said finger has substantially reached the limit of its rearward movement. 115

6. Feeding mechanism for packaging machines including a transfer head having notches formed therein, means for feeding articles into the path of said transfer head to be engaged thereby, a cover plate and studs adjustably carried by said cover plate and extending into the path of the notches in the transfer head for holding articles in 125 their bunched position until engaged by said head. 130

6

7. Feeding mechanism for packaging machines, including a feed hopper, endless conveyors for feeding the articles from said hopper along substantially the same horizontal plane, and means for receiving and directing the articles from each of the endless conveyors along a different horizontal plane from the articles delivered from the remaining conveyors.

10. Feeding mechanism for packaging machines, including a feed hopper having a plurality of compartments arranged therein, endless conveyors for feeding the articles from each of said compartments, said endless conveyors having grooves formed therein, and platforms arranged in different horizontal planes and having fingers extending into the grooves for directing the articles from each of the endless conveyors along a different horizontal plane from the articles delivered from the remaining conveyors.

9. Feeding mechanism including a compartment, a plunger for feeding articles through said compartment, a reciprocating cross head pivotally connected with said plunger, and resilient means for normally

holding said plunger out of alignment with the compartment.

10. Feeding mechanism including a compartment, a plunger for feeding articles therethrough, a roller carried by said plunger, a cam bar in position to engage the roller to move and hold the plunger out of alignment with the compartment, and a cam for engaging the roller to move the plunger into alignment with the compartment against the action of the cam bar.

11. Feeding mechanism including a compartment, a plunger for feeding articles therethrough, a roller carried by the plunger, a pivoted cam bar in position to engage the roller to move and hold the plunger out of alignment with the compartment, a spring connected with the cam bar for resiliently opposing pivotal movement thereof, and a cam for engaging the roller to move the plunger into alignment with the compartment against the action of the cam bar and spring.

In testimony whereof I affix my signature.

IGNACIO LAZAGA.
